DES. 2014

Nicholas G. Vodden, of Troy, N.Y.

Letters Patent No. 3014. Dated Decr 13-1864.

Design for a Stove plate.

The schedule referred to in these Letters Patent and making part of the same.

shall be known as my combination.

Bethel Brown and I, Nicholas G. Vodden
of the City of Troy, in the County of Rensselaer, and State of New
York, have invented or produced a certain new and origi-
nal ornamental Design for Stove Plates; and I do hereby de-
clare that the following is a full, exact, and description of
the same, reference being had to the accompanying
photograph of a stove plate bearing my said ornamental
design.

This ornamental design consists of a swelling cir-
cular or oval shield-like ornament having a alternate
raised and depressed parallel bands of the mid with sides
of a central beaded rim, and within a circular or oval
moulding, bearing along the opposite sides, strings of
beads R.R supported by scroll-shaped holders U.U having
scroll-shaped ends, m.m.m.m.m. which are held together
with the scroll-like ends u.u.u.u of the central beaded
rim, by rings e.e the whole being shaped and arranged
together on a panel P of a stove-plate so as to present the
appearance represented by the accompanying photograph.

What I claim as new and of my invention or produc-
tion, and desire to secure by Letters Patent, is the above de-
scribed ornamental design for stove plates.
